Primary Examiner — Kevin K. Rudzinski*Assistant Examiner* — Kathleen L. Jones(74) *Attorney, Agent, or Firm* — Fox Rothschild LLP(57) **CLAIM**

The ornamental design for a suppressor tool, as shown and described.

DESCRIPTION

FIG. 1 is an isometric view of a suppressor tool according to the present disclosure;

FIG. 2 is a front view of the suppressor tool of FIG. 1;
FIG. 3 is a rear view of the suppressor tool of FIG. 1;
FIG. 4 is a right side view of the suppressor tool of FIG. 1;
FIG. 5 is a left side view of the suppressor tool of FIG. 1;
FIG. 6 is a top view of the suppressor tool of FIG. 1;
FIG. 7 is a bottom view of the suppressor tool of FIG. 1; and,
FIG. 8 is an isometric view of the suppressor tool of FIG. 1 in environmental use.

The broken lines in the figures showing portions of the suppressor tool and environmental structure in FIG. 8 form no part of the claimed design.

1 Claim, 4 Drawing Sheets(56)
